UNITED STATES PATENT OFFICE.

WILLIAM C. BOOTS, OF ATTLEBORO, MASSACHUSETTS, ASSIGNOR TO GUYOT BROTHERS CO. INC., OF ATTLEBORO, MASSACHUSETTS.

WATCH-BRACELET END FASTENER.

Application filed April 30, 1927. Serial No. 187,891.

This invention relates to certain new and useful improvements in watch bracelet end fasteners, and the primary object thereof is to provide means for adjustably connecting an end of a watch strap to the fastener. As is well known in the art, in the instance of the use of leather or other straps subject to stretching such straps, after varying periods of use, become stretched so that the latter loosely fit the wrist of the wearer with the result that the watch is continually being shifted from one position to another. The present invention, therefore, aims to provide means whereby upon stretching of the strap, same may be disengaged from the fastener and a short piece thereof cut off, and the strap then re-secured to the fastener.

The invention further aims to provide a device of this type wherein the parts are of simple and economical structure and are compactly related so as to occupy a minimum of space.

The invention still further aims to provide a device of this kind wherein the pivoting means for the guard of the hook of the fastener acts to also limit movement of the strap clamp in one direction of movement of the clamp.

In the drawings:—

Figure 1 is a bottom plan of the invention applied to a strap, and

Figures 2, 3 and 4 are sections on line 2—2, 3—3 and 4—4 respectively of Figure 1.

In proceeding in accordance with the present invention a fastener member is employed which is composed of a back 1 having a hook 2 at one end thereof, the sides of the back are bent inwardly or doubled upon themselves to provide sides 3 of double thickness. The doubled parts are perforated and receive a transverse pin 4 therein. A substantially L-shaped guard 5 is employed the front side of which engages the hook 2 and which is formed with an intermediate outwardly projecting lug 8 that is perforated to receive one end of a spring 6, the opposite end of the spring abutting the back 1. The spring 6 is coiled about a sleeve 7 mounted on the pin 4. The guard is further formed with rolled eyes 9 that engage over the sleeve 7 thereby to pivotally mount the guard. A substantially L-shaped clamp 10 is provided with a serrated edge 11 which engages the strap S. The clamp is formed

with pintles 12 which engage in openings 13 provided therefor in the doubled portions of the sides 3. The sleeve 7 may be dispensed with if desired.

By referring to Figure 1 of the drawing, it will be noted that the rear of the guard is provided with a substantially semi-circular cut-out 14 while the clamp is formed with a forwardly projecting tongue 15 which is curved to fit in the cut-out 14.

The tongue at its free end is bent outwardly at a slight angle so as to enable a fingernail of the user to be engaged therebeneath. It will further be noted that the tongue 15 overlies the pin 4 and its sleeve 7 and consequently the latter parts act to limit movement of the clamp in one direction.

From the foregoing it will be noted that due to the nested relation of the parts 15 and 14 of the guard and clamp a compact assemblage of the elements is afforded.

In operation, it will be noted that the guard may be easily and quickly moved to permit the hook 2 to engage over the usual bail carried by the side of the watch and that by engaging the fingernail with the tongue 15 of the clamp 10, the latter may be disengaged so as to release the strap S thereby to permit of cutting and adjusting of the strap as may be desired.

Having thus described my invention what I claim as new and desire to secure by Letters Patent is:—

1. In a watch bracelet end hook, a member having a back provided with spaced sides and a hook at one end thereof, a transverse pin secured to the sides intermediate the ends of the latter, a spring tensioned guard for the mouth of the hook extending across the latter and pivoted to the pin, said guard having its front side engaging the hook and its rear side formed with a cut-out, and a bracelet clamp consisting of a substantially L-shaped member pivoted to and between the sides of the back at the opposite end thereof and having a serrated bracelet engaging edge at one side thereof and having its opposite side formed with a forwardly projecting finger nail engaging tongue which latter is received in the cut-out of the guard and overlies the pin so as to have its movement in one direction limited by the pin.

2. In a watch bracelet end hook a member having a back provided with spaced sides

and a hook at one end thereof, a transverse pin secured to the sides intermediate the ends of the latter, a spring tensioned guard for the mouth of the hook extending across the latter and pivoted to the pin, said guard having its front side engaging the hook, and a bracelet clamp consisting of a substantially L-shaped member pivoted to and between the sides of the back at the opposite end thereof and having a serrated bracelet engaging edge on one side thereof and having its opposite side formed with a forwardly projecting fingernail-engaging tongue which latter overlies the pin so as to have its movement in one direction limited by the pin.

3. In a watch bracelet end hook, a member having a hook on one end thereof, a pin connected to the member intermediate the ends thereof, a spring tensioned guard for the mouth of the hook pivoted to the pin, a bracelet clamp pivoted to the member to the rear of the guard, and operating tongue for the clamp carried thereby and overlying the pin so as to have its movement in one direction limited by the pin.

4. In a watch bracelet end fastener, a member having a hook on one end thereof, a spring tensioned guard for the hook, means to pivotally connect the guard to the member, said guard having a cut-out, a bracelet engaging clamp pivoted to the member to the rear of the guard, and an operating tongue carried by the clamp and receivable in the cut-out of the guard, said tongue being engageable with said means to pivotally

connect the guard to the member and having its movement in one direction limited thereby.

5. In a watch bracelet end fastener, a member having a hook on one end thereof, a spring tensioned guard for the hook, means to pivotally connect the guard to the member, said guard having a cut-out, a bracelet engaging clamp pivoted to the member to the rear of the guard, and an operating tongue carried by the clamp and receivable in the cut-out of the guard.

6. In a watch bracelet end fastener, a member having a hook on one end thereof, a pivoted spring tensioned guard on the member cooperating with the hook, a bracelet engaging clamp pivoted to the member to the rear of the guard and disposed in substantially the plane of the hook, and an operating tongue carried by the clamp and arranged in substantially the plane of the guard and having a free front end disposed at a point between the front and rear of the guard.

7. In a watch bracelet end fastener, a member having a hook at one end and on a side thereof, a tensioned guard on the member cooperating with the hook, and a bracelet engaging clamp pivoted to said member on said side thereof and having an operating tongue which latter has a free end extending past the rear of the guard and has its free end curved outwardly.

In testimony whereof I have signed my name to this specification.

WILLIAM C. BOOTS.
